PLATE VALVE

William E. Bebbington, Painted Post, N. Y., assignor to Ingersoll-Rand Company, Jersey City, N. J., a corporation of New Jersey

Application March 20, 1931, Serial No. 523,992

6 Claims. (Cl. 251—119)

This invention relates to valve mechanisms, but more particularly to a plate valve for use in connection with compressors for controlling either the admission of fluid into the compressor or the discharge of fluid therefrom, depending upon whether the valve is intended to serve the function of an inlet valve or of a discharge valve.

One object of the invention is to prevent sharp and consequent noisy impact of the valve plate against the stop elements which limit its range of movement.

Another object is to allow the initial unseating movement of the valve plate to take place against comparatively light resistance and to assure an increased cushioning action upon the valve plate during the subsequent or final portion of the unseating movement of said valve plate.

Other objects will be in part obvious and in part pointed out hereinafter.

In the drawings accompanying this specification and in which similar reference characters refer to similar parts,

Figure 1 is a sectional elevation of a plate valve constructed in accordance with the practice of the invention.

Figure 2 is a perspective view of the plate valve.

Figure 3 is a similar view of a guide member for the valve plate.

Figure 4 is a perspective view of the spring plate.

Figures 5, 6 and 7 are side elevations of the plate valve illustrating limiting and intermediate positions of the reciprocable parts during the unseating movement of the valve plate.

Figure 8 is a side elevation of a modified form of spring plate, and

Figure 9 is a side elevation of a valve mechanism equipped with a spring plate of the form illustrated in Figure 8.

Referring to the drawings and at first more particularly to the preferred form of construction illustrated in Figures 1 to 7 inclusive, A designates generally a plate valve comprising a valve seat B, a stop plate C which is secured to the valve seat B by means of a bolt D, and a nut E threaded on the bolt D.

Interposed between the valve seat B and the stop plate C is a washer or guide member F through which the bolt D also extends. The washer F determines the width of a space G between the valve seat B and the stop plate C. The peripheral surface H of the washer F acts as a guide surface for a valve plate J dis-

posed in the space G to control ports K in the valve seat B and through which fluid may pass to or from the compressor, depending upon whether the valve assembly is being used as an inlet valve or as a discharge valve.

The ports K may be of any suitable number and extent to assure port area commensurate with the requirements of the compressor. The stop plate C may, as illustrated, be provided with similar ports L to provide ample passage for the fluid issuing from or flowing to the ports K.

The ports K and L may assume any desired shape as for instance, arcuate and the valve plate J is therefore also preferably provided with arcuate ports O through which the fluid may flow from the ports K to L, or vice versa. The ports O in the valve plate J are of course so arranged that in the assembled position of the parts, the said ports O will lie in the same transverse plane as the ports L in the stop plate and will therefore be staggered with respect to the ports K.

In order to maintain the weight of the valve plate J to a minimum and also to avoid overlapping portions of unnecessarily large extent on the valve plate J and the valve seat B, the washer F may be of such diameter that its peripheral surface H lies closely adjacent the inner port K. When so arranged, the washer F may be provided with slots or notches P of suitable area to provide channels for pressure fluid flowing from the innermost ports K to the innermost ports L in the stop plate.

In accordance with the present invention, means are provided to effect adequate cushioning of the valve plate J during the unseating movement of said valve plate. To this end the valve mechanism is provided with a spring plate designated generally by Q which is interposed between the valve plate J and the stop plate C. The spring plate Q comprises an inner, preferably uninterrupted, annular body portion R having a central opening S to receive the washer F.

On the outer edge or periphery of the body portion R are a plurality of lateral extensions T, three being shown in the present instance, and at the outer ends of the extension are spring arms U which are curved to correspond to the curve of the body portion R and with respect to which they are suitably spaced. Preferably the outer diameter of the spring plate, that is, from the outer edge of one spring arm to another, taken through the median line of the spring plate, substantially equals the diameter

of the valve plate J upon which the free ends V of the spring arms U are adapted to constantly bear.

The spring arms U are continuously curved 5 out of the plane of the spring plate R and at a point beginning preferably at the point of union of the spring arms and the extensions T so that all portions of said spring arms are initially bent out of the plane of the body portion 10 R. In this respect they differ from types of spring arms heretofore proposed and wherein the spring arms were merely bent out of the plane of the spring plate so that the arms in effect were straight uncurved members and 15 which members, upon the application of pressure to the free ends thereof, would merely yield or bend at the point or angle at which they joined the normal portions of the spring plate.

In order that the bending movement of the 20 arms U may not be confined to one particular region of the arms, as is customary in devices of this character as heretofore constructed, said arms are preferably of the same width and thickness and consequently of the same cross sectional area throughout their lengths.

In practice, assuming the parts comprising the valve mechanism to be suitably assembled and arranged in the compressor and in the case of a discharge valve, such as that illustrated, the 25 fluid being compressed will act against the surface of the valve plate J adjacent the ports K and will unseat the valve plate, whereupon the fluid being compressed will be discharged from the compressor.

During the initial movement of the valve plate, 30 said valve plate will encounter comparatively light resistance by the spring fingers U. This is due to the fact that the spring fingers are of considerable length. As the valve plate J approaches an intermediate position in the space G, for instance as illustrated in Figure 6, the spring arms U will be raised in the direction of the stop plate C wherewith they will contact at 35 a point intermediate their ends as for instance that designated by W in Figure 6.

In mechanisms wherein the spring plate Q is capable of free movement relatively to the stop plate C this upwardly applied pressure of the valve plate against the free ends of the spring 40 fingers will result in drawing the spring plate bodily in the direction of the valve plate J.

It follows therefore that, as the valve plate J approaches the end of its unseating movement, the attached ends of the arms U are moved 45 free of the stop plate C to meet and contact with the approaching valve plate J. Thereafter the portions of the arms lying on opposite sides of what may be termed the initial point of contact or fulcrum W will be gradually rolled back 50 against the stop plate, thus increasing the areas of contact between the arms U both in the direction of the free ends and the attached ends of said arms. In consequence, the unsprung portions of the arms U are gradually diminished.

Owing to this fact a relatively greater resistance 55 is offered by the ends of the arms to the valve plate during the final unseating movement thereof than is exerted by the arms during the initial unseating movement of the valve plate.

This is highly desirable in apparatus of this 60 character as it prevents the valve plate J from impacting sharply against the elements which act as a stop therefor, for example, the spring plate, as well as the sharp impact of the spring 65 plate against the stop plate C.

It may be desirable in some forms of usage to avoid movement of portions of the spring plate other than the spring fingers. In such case, of course, only the resistance of those portions of the arms U lying entirely on one side of the extensions T would serve to resist or cushion the opening movement of the valve plate J. With only the arms U capable of movement, said arms will be rolled along the surface of the stop plate C, thus gradually shortening the 80 unsprung portions of said arms and in this way assuring maximum cushioning pressure of the arms on the valve plate J during the final opening movement of the said valve plate.

In the modified form of spring plate shown 85 in Figures 8 and 9 and designated by X, the spring arms Z have reversely curved portions b and c. The curved portions b, which are those adjacent the lateral extensions T, may be of comparatively short radius or of an extent which 90 will carry the adjacent part of the curved portions c above or to one side of the main body portion R' of the spring plate. The portions c are then gradually curved on a larger radius than the portions b to pass through the plane of 95 the body portion R' so that the free ends d of the arms Z will lie on the opposite side or below the body portion R' as Figure 8 is viewed in the drawings.

A spring plate constructed in accordance with 100 the practice of this modification will, as is more particularly illustrated in Figure 9, assure prompt depressions of the attached portions of the spring arms during the initial unseating movement of the valve plate J. Moreover, this 105 form of the invention is also particularly applicable for use in valve mechanisms wherein high lift of the valve plate J may be essential.

The cushioning effect, however, of the spring 110 plate X, or, more specifically, the arms Z, is 115 in all essential respects like that of the spring plate Q, that is, in the case of a free floating spring plate X the force exerted by the valve plate J against the free ends d of the fingers Z 120 will tend to move the attached ends or portions 125 of the arms in the direction of the valve plate to contact therewith. The arms Z will then contact with the stop plate at a point intermediate the ends of the arms, and during the 130 subsequent unseating movement of the spring 135 plate J the portion of the arms Z lying on the opposite sides of the point of initial contact of the arms Z with the stop plate will be rolled back so that as the unsprung portions of the 140 arms Z decrease, the cushioning effect thereof 145 will increase correspondingly.

I claim:

1. A plate valve comprising a valve seat having ports therein, a stop plate, a valve plate reciprocable between the valve seat and the stop plate to control the ports, a spring plate movably disposed between the valve plate and the stop plate, and spring arms on the spring plate to press the valve plate to the valve seat and being continuously curved in the direction of the valve plate throughout their lengths, whereby intermediate portions of the arms seat against the stop plate upon the initial opening movement of the valve plate and the portions of the arms lying on opposite sides of said intermediate portions cushion the subsequent or final opening movement of the valve plate.

2. A plate valve comprising a valve seat having ports therein, a stop plate, a valve plate reciprocable between the valve seat and the

- stop plate to control the ports, a spring plate between the stop plate and the valve plate, and spring arms on the spring plate of uniform cross-sectional area throughout their lengths and constantly pressing with one end against the valve plate, said arms being bent out of the plane of the spring plate and curved throughout their lengths, whereby the intermediate portion of each arm is raised above the ends of said arms to initially seat against the stop plate and the portions of the arms lying on opposite sides of said intermediate portions of initial contact cushion the subsequent or final opening movement of the valve plate.
- 5 3. A plate valve comprising a valve seat having ports therein, a stop plate, a valve plate reciprocable between the stop plate and the valve seat to control the ports, a spring plate movably disposed between the valve plate and the stop plate, means for holding the stop plate in spaced relation with respect to the valve seat and to guide the valve and spring plates, and curved arms attached at one end to the spring plate constantly bearing with the other end against the valve plate, said arms being of uniform cross-sectional area throughout their lengths whereby upon the initial opening movement of the valve plate an intermediate portion of each arm will seat against the stop plate and the attached ends of the arms will be moved in the direction of the valve plate to assist the free ends of the arms in cushioning the final opening movement of the valve plate.
- 10 4. A plate valve comprising a valve seat having ports therein, a stop plate, a valve plate reciprocable between the stop plate and the valve seat to control the ports, a flat spring plate reciprocable between the valve plate and the stop plate and having a bore, spring arms on the spring plate concentric therewith and having free ends pressing against the valve plate and being initially curved out of the plane of the spring plate throughout their lengths and in a continuous curve whereby during the unseating movement of the valve plate the area of contact between the spring arms and the stop plate will gradually increase and the unsprung portions of the arms will correspondingly decrease toward both extremities of each spring arm to effect maximum cushioning pressure on the valve plate during the final unseating movement thereof, and a spacer between the valve seat and the stop plate extending through the bore in the spring plate to guide said spring plate.
- 15 5. A plate valve comprising a valve seat having ports therein, a stop plate, a valve plate reciprocable between the stop plate and the valve seat to control the ports, a spring plate between the stop plate and the valve plate and having an inner annular body portion, lateral extensions on the body portion, spring arms connected at one end to the extensions and being arranged concentrically with respect to the body portion, said spring arms being spaced with respect to the body portion, and being curved continuously from one extremity to the other whereby, upon the application of pressure to the free ends of the spring arms, the intermediate portions of the spring arms are raised above the extremities of said arms to initially seat against the stop plate and the portions of the arms lying on the opposite sides of the point of initial contact cushion the subsequent movement of the valve plate in the direction of the stop plate.
- 20 6. A plate valve comprising a valve seat having ports therein, a stop plate, a valve plate reciprocable between the stop plate and the valve seat to control the ports, a spring plate between the valve plate and the stop plate and having lateral extensions thereon, and spring arms on the lateral extension and being arranged concentrically with respect to the spring plate, said arms comprising comparatively long continuously curved portions extending through the transverse plane of the spring plate and short reversely curved portions between the long portions and the extensions.
